United States Patent Office

Des. 193,690
Patented Sept. 25, 1962

193,690

CARTON FOR FRUIT OR THE LIKE

Verne Hayes, Eureka, Calif.

Filed Mar. 4, 1960, Ser. No. 59,613

Term of patent 14 years

(Cl. D58—11)

FIG. 1

FIG. 2

FIG. 3

FIG. 4

FIG. 1 is a top plan view of a carton for fruit or the like, showing my new design.

FIG. 2 is a front elevational view thereof.

FIG. 3 is a bottom plan view thereof, and

FIG. 4 is a vertical sectional view taken along the line 4—4 of FIG. 1.

I claim:

The ornamental design for a carton for fruit or the like, as shown.
